UNITED STATES PATENT OFFICE.

THOMAS R. CRANE, OF HEATHSVILLE, VIRGINIA.

FERTILIZER-FEED FOR DRILLS.

SPECIFICATION forming part of Letters Patent No. 377,546, dated February 7, 1888.

Application filed November 3, 1887. Serial No. 254,152. (No model.)

To all whom it may concern:

Be it known that I, THOMAS R. CRANE, a citizen of the United States, residing at Heaths-ville, in the county of Northumberland and 5 State of Virginia, have invented certain new and useful Improvements in Fertilizer-Feeds for Drills, of which the following is a specification.

My invention relates to certain improvements in agitators of fertilizer-feeds for drills; and said invention is hereinafter first described, and then pointed out in the claim.

Referring to the accompanying drawings, Figures 1 and 2 show broad and narrow side 15 views of the agitator device. Figs. 3, 4, and 5 each show an agitator-foot, the top part of which has a different shape, but each a like blunt face and sharp back. Fig. 6 is a vertical cross-section of the hopper, showing the 20 agitator in position. Fig. 7 is a top plan, being a horizontal section of the hopper and a view of the agitator. Fig. 8 is a view of the shaft bearing on the outside of the end of the hopper. Fig. 9 is a vertical section of the 25 same. Fig. 10 is a horizontal section of the same.

The letter A designates the hopper or box to receive the fertilizer, and which has a concaved bottom, b, provided with discharge- 30 openings c. A rock-shaft, G, extends longitudinally through the hopper, and has its ends supported in adjustable bearings d, secured to the ends F. Each of the two ends has an opening, e, which is closed by the bearing-plates d, which may be moved or adjusted vertically 35 sufficient to locate the agitator-foot o in the proper relative position with respect to the bottom b. The bearing-plate d has a central boss, i, which occupies the opening e, and 40 which is provided with a hole for the journal end h of the rock shaft. It also has a flange, j, which bears against the outer surface of the end F, and said flange has two slots, k. A bolt or set-screw, l, occupies each slot and enters the end F. The loosening of the screws l will allow the bearing-plate to be vertically 45 adjusted, and thereby raise or lower the rock-shaft G, and the feet o of the agitators may be brought as close to the bottom b as desired.

While this result is desired, another object is 50 attained by my construction that is important—to wit, the rock-shaft G and agitators may be removed from the hopper without detaching either the hopper ends F or the agitators I. To remove the rock-shaft it is only 55 necessary to take off the bearing-plates d, which, being on the outer surface of the hopper ends F, can be readily done. When the plates d are off, the openings e in the ends are exposed. The rock-shaft may then be moved 60 endwise, so that one journal end will project through one of the said openings e far enough to entirely withdraw the opposite journal end from the other opening e. The latter end may then be raised and the entire rock-shaft re- 65 moved.

The agitators I on the rock-shaft have three prongs, n, and each side prong has a foot, o, of peculiar shape. The peculiarity of this foot is that on one side it has a blunt face, o', which 70 in swinging one way will push the fertilizer to the discharge-opening b, and on the opposite side the foot has a sharp or knife-edge back, o'', which in swinging the opposite way will cut under the fertilizer. This foot is well 75 suited for a vibrating agitator. So far as concerns the plan shape of this foot, that is immaterial. It may be rectangular, as in Figs. 1, 2 and 3. Its push-face o' may have the form of an obtuse angle, as in Fig. 4, or the push-face may be a simple concave, as in Fig. 5.

Having described my invention, I claim and desire to secure by Letters Patent of the United States—

In a fertilizer-hopper, the combination of 85 the bottom having discharge-openings c, and the vibrating agitator I, having two side prongs, n, each provided with a foot having at one side a blunt push-face, o', and at the opposite side a knife-edge back, o'', for the purpose 90 set forth.

In testimony whereof I affix my signature in the presence of two witnesses.

THOMAS R. CRANE.
